UNITED STATES PATENT OFFICE.

ELMER F. CASSEL, OF SEATTLE, WASHINGTON.

CIPHER-CODE SYSTEM.

SPECIFICATION forming part of Letters Patent No. 657,586, dated September 11, 1900.

Application filed March 10, 1900. Serial No. 8,153. (No specimens.)

To all whom it may concern:

Be it known that I, ELMER F. CASSEL, of Seattle, in the county of King and State of Washington, have invented certain new and useful Improvements in Cipher-Code Systems; and I do hereby declare the following to be a full, clear, and exact description of the invention, such as will enable others skilled in the art to which it appertains to make and use the same.

This invention relates to certain new and useful improvements in cipher-code systems for use in transmission of cable, telegraphic, and other forms of written messages.

15 The invention has for one object the production of a simple and concise cipher-code system whereby liability to error in transmission is reduced to a minimum or entirely overcome.

20 A further object is to provide a cipher-code system which can be readily and easily comprehended and accurately used by a novice in the making up and deciphering of cipher-messages.

25 A further object is to produce a simple and concise cipher-code system which is particularly applicable for the transmission of tabulated matter.

30 A further object is to produce a cipher-code system whereby the general code is readily convertible without complicated rules or mechanism into a private code for use between two or more individuals.

35 A further object is to provide a cipher-code system which is so flexible in its application as to be susceptible of universal employment.

In carrying out my invention I employ a system of cipher-words, one portion of the word being used to designate the group—*i. e.*, 40 the page, column, or section—containing the desired message, and the other portion of said word indicating the line or definition on said page, column, or section embodying the message to be transcribed, the whole forming a 45 complete arbitrary cipher-word without literal meaning and forming the key by means of which the desired message can be readily and quickly located in the code-book.

The invention will be hereinafter fully set 50 forth, and particularly pointed out in the claims.

In the accompanying drawings, Figures 1

and 2 are views of pages from my improved cipher-code system. Figs. 3, 4, 5, and 6 are similar views of modifications.

Referring to the drawings, A A' represent consecutive pages of my improved cipher-code system. On each page, preferably near one corner thereof, is placed that portion B of the cipher-word which is designed to indicate the particular page upon which the message is found and by which said page is known, it being understood, of course, that each page is designated by a separate and distinct word or syllable. Each page contains a series of 65 definitions C, arranged in lines, as shown, and opposite each line is placed that portion D of the cipher-word by which the particular line is designated. The two portions B and D when united form a complete cipher-word without 70 literal meaning and in such form that the receiver can readily and quickly find the desired definition in the code-book. The portions D of the cipher-word are arranged in columns on each page, as at E. By reference to the drawings it will be seen that the portion of the cipher-word indicating the line may be the same for the corresponding line on each page, regardless of the number of the 75 pages or the definitions therein contained. 80

While I have illustrated and described the definitions C as contained on separate pages, yet it is obvious that, if desired, different sets of definitions may be arranged in columns on one page, said columns being designated by 85 that portion B of the cipher-word which I have described as being used to designate the page.

In Fig. 3 I have shown a slight modification of my improved cipher-code system, this form 90 being designed more particularly for use in connection with tabulated work. In this form that portion of the cipher-word F indicating the line is employed in the same manner as in the form heretofore described, and in lieu 95 of the definitions a series of dimensions G are arranged on the same line therewith. Corresponding with said dimensions are a series of measurement G', the same being arranged in columns H, as shown. In lieu of designating each page by a portion of the cipher-word the latter is applied to each column H, as indicated at I, accomplishing the same result. The code illustrated in Fig. 5 is de- 100

signed particularly for the lumber trade, although it is quite obvious that the same can be modified to suit any form of tabulated work without departing from the spirit of my invention.

In Figs. 4, 5, and 6 I have shown a second modified form of my improved cipher-code system, the same being particularly adapted for the transmission of numbers for any purpose whatever. The numbers are preferably arranged in lines J and range from "000" to "999," each line being designated by a portion of the cipher-word, as heretofore described. Said numbers are also divided into 15 columns K, each column being designated by a portion of the cipher-word, as in the form illustrated in Fig. 3. When it is desired to transmit a number, the same is written down by the operator and divided from the right in 20 groups of three figures, the ordinary method of numeral notation. The cipher-word of the first of said groups from the left is then written, the same being made up of the portions indicating the line and column. This is followed 25 by the cipher-word for the next group, and so on until the entire number is written. For example, assume that the number "1,009,195" is to be written, the same would be indicated by the following cipher-words: 30 "Snackfall Stackfall Shackfit." If desired, the suffix "ing" or some similar symbol may be added to each of the first two cipher-words to indicate that the figures designated by the next cipher-word are part of the same number. 35 Should this system be followed out, the foregoing number would be indicated as follows: "Snackfalling Stackfalling Shackfit."

From what has been said it will be readily perceived that by means of my improved system any conceivable number can be accurately transmitted and the use of a voluminous code, as is now the practice, is entirely obviated.

In the form illustrated in Figs. 1 and 2 when a cipher-message is transmitted the desired information is indicated by an arbitrary cipher-word, which is made by uniting that portion B indicating the page with that portion D indicating the line containing the 45 desired definition, or when the other forms are employed the cipher-word is formed by compounding the portion indicating the column with the portion indicating the line. An illustration of the latter has been given 50 in connection with the transmission of numbers. To illustrate the former, it will be assumed that the following message is to be transmitted, to wit: "Your letter received. Will wire full particulars." Said message 55 would be contained in the two cipher-words "Dumbfall Dawnflip," the first portion of each word indicating the page containing the definition or phrase and the second portion the line on said page containing the message. 60 It will be particularly noted, however, that while I have described the first half of the cipher-word as indicating the page or col-

umn and the latter half the line, yet these may be transposed without departing from the spirit of my invention.

The advantages of my improved cipher-code system are apparent. It will be particularly noted that those parts of the cipher-words used to designate the lines of the page, column, or section can always remain the 75 same. Another important advantage lies in the conciseness of my improved system. For instance, cipher-codes now in general use employ a different cipher-word for each definition or item to be transcribed. Thus it 80 will be seen that a code containing twenty-five thousand definitions would require the selection of a corresponding number of cipher-words. It is obvious that the selection of such a large number of words which will 85 be free from error in transmission, particularly telegraphic transmission, is practically impossible. The principal reason for this lies in the fact that a cipher-word to be absolutely accurate and intelligible must be 90 arbitrary and not easily mistaken for other than a cipher-word—i. e., it must be absolutely without literal meaning in the body of a message. A very large percentage of the 95 cipher-words now in use consists merely of an aggregation of letters, and a very large portion of these are so arranged as to be peculiarly susceptible of error in telegraphic transmission, as is well known to those who make constant use of ciphers in the transaction of business. By means of my improved system a cipher-code of twenty-five thousand definitions can be constructed with the use of but five hundred and fifty word parts or 100 syllables, which latter can be obviously selected with especial reference to accuracy in transmission by telegraph. In other words, a code consisting of five hundred pages of fifty lines to a page would contain twenty-five thousand definitions requiring five hundred 105 page or column words or syllables and fifty line words or syllables. Inasmuch as the cipher-word is formed by uniting the portion of the word indicating the page or column and that indicating the line to form a 110 compound word designating the definition, it will be readily seen that the same fifty line words or syllables can be employed on each page. The words or syllables thus used 115 can be selected from words of every-day use and well-understood meaning, for the reason 120 that such meaning is absolutely destroyed just as soon as any two of them are united into one complete cipher-word. Aside from this, however, its very construction would 125 designate it as a cipher-word.

One of the greatest causes of error in telegraphic transmission of cipher-words now in use and formed of a meaningless aggregation of letters is principally due to the fact that 130 the receiving operator has nothing to guide him in determining whether or not he has received it correctly. By the use of my system this difficulty is entirely avoided.

It is also apparent that my improved cipher-code system can be readily changed into a form for private use by substituting new words or syllables for those already in use indicating the page or column, or substituting new words or syllables for those indicating the lines, or the latter may remain the same and their positions varied, all of which is contemplated by my invention. My improved cipher-code also contemplates the substitution of numbers or figures in lieu of words or syllables for designating the pages or columns and the definitions therein contained.

I claim as my invention—

- 15 1. A cipher-code in which words or syllables capable of literal translation are so compounded as to form a complete cipher-word without literal meaning, as set forth.
- 20 2. A cipher - code in which single code words or characters are formed of two united parts or syllables indicating respectively a definition and a group of definitions, as set forth.

3. A cipher-code consisting of a series of groups each indicated by a word or syllable 25 and containing a series of definitions, each of which latter is also designated by a word or syllable, said words or syllables when united forming a cipher-word without literal meaning, as set forth.

4. A cipher-code consisting of a series of groups each indicated by a word or syllable and containing a series of definitions, each of which latter is also designated by a line word or syllable, said line words or syllables 35 being the same for each group, arbitrary cipher-words being formed by compounding said page and line words or syllables, as set forth.

In testimony whereof I have signed this 40 specification in the presence of two subscribing witnesses.

ELMER F. CASSEL.
